(57) CLAIM

The ornamental design for a junction box bracket, as shown and described.

DESCRIPTION

FIG. 1 is a perspective view of a junction box bracket depicting a first embodiment of a new design;

FIG. 2 is a first side view thereof;

FIG. 3 is a second view thereof;

FIG. 4 is an end view thereof;

FIG. 5 is an opposite side end view thereof;

FIG. 6 is a top plan view thereof;

FIG. 7 is a bottom plan view thereof; and,

FIG. 8 is an additional perspective view thereof.

The broken line portion of the figure drawings is included to show unclaimed subject matter only and forms no part of the claimed designs.
